ATTORNEY.

UNITED STATES PATENT OFFICE

KENNETH G. WILLIAMS, OF ST. PAUL, MINNESOTA

ELECTRIC BELL-SOUNDING DEVICE FOR CLOCKS

Application filed March 29, 1928. Serial No. 265,789.

This invention relates to a new and improved device for sounding a bell or other alarm means such as used in clocks and comprises a part of my application for patent on 5 electric clock Serial No. 194,069 filed May 25, 1927 in the United States Patent Office.

The object of the invention is to provide certain electrically operated toll means for 10 clocks either electrically or mechanically operated, as hereinafter set forth and as illustrated in the accompanying drawing, in which,—

Fig. 1 is a schematic electric diagram of my device and including the bell sounding means. 15 Fig. 2 is a vertical elevation of a clock-work frame, its time indicating bell, my device mounted in operative position, and some of the gear means of a clock pertaining particularly to the striking mechanism.

20 Referring to the drawing by reference numerals, 5 designates one of two main frame plates of a clock between which are mounted the usual gears, spring and other words rotating the time indicating hands not shown. 25 6 is a so called striking gear with a shaft 7 journaled in the frame and a brace 8 fixed parallel thereto, said gear having a pinion 6P fixed adjacent to its inner side (not shown) meshing at certain times with an intermediate gear 9 rotated by a pinion 10 30 which is rotated by a main spring of the clock or other means (not shown). The latter pinion is fixed on a shaft 11 and gear 9 is mounted on a shaft 12 both journaled suitably in 35 the clock frame.

The striking gear 6 has the usual peripheral shallow teeth 6A and deep notches 6B which control the toll sounding means, usually released at the hour and half hour periods.

40 The pinion 6P with gear 6 does not mesh with gear 9 except when the bell sounding means are to be operated, being thrown into mesh with said gear 6 at these intervals by suitable means. The teeth and notches of 45 said gear are engaged by the flat tooth 13 which is part of the clock mechanism described in said other application or equivalent means in spring driven clocks. When 50 said pinion 6P is meshed with the moving

clock gear 9 at fixed intervals gear 6 is driven in left hand direction or as indicated by arrow 14 in Fig. 2 and tooth 13 rides on the gear teeth 6A until it drops into a notch 6B, when the striking means, presently to be described 55 cease to strike the bell 15, as said dropping of tooth 13 into a deep notch causes the gear 6 and its pinion 6A to be moved out of engagement from the gear 9 and remains idle until time for the next signal.

60 In Fig. 2 I have shown tooth 13 fixed to the under side of a lever 16 pivoted at 17 in the frame 5, said bar being of course oscillated vertically when the tooth 13 rides the teeth 6A. This oscillating movement causes 65 circuit closing contact of a contact member 18, on outer end of bar 16 with another contact plate 19 close above it (see Fig. 2) both in a circuit 20 (see Fig. 1), plate 19 being energized by current from any available electric source designated 21. Circuit is completed through said contacts and a wire 22 to a double magnetic core 23 suitably fixed in the upper part of the clock frame (see Fig. 70 2). The magnetic core is of course thus charged by current to operate a certain mechanical device to ring the bell 15 as will now be described.

75 The striking means comprises a bell hammer 24 at the lower end of an upright arm 25 fixed on a beam lever 26 fulcrumed on a horizontal shaft 27 in the upper part of a frame extension arm 5A at the upper central part of the frame and said lever 26 normally in vertical plane. 28R and 28L are respectively right and left reach rods, one as 28R pivoted to upper end of lever 26 and 28L pivoted to lower part of said lever, the outer ends of said rods pivoted respectively to a right hand lever 29R and a left lever 29L 80 both adapted to be oscillated in vertical plane each on a rock shaft 30 fixed one at each upper corner of the main frame 5. The free end of each lever (29R and 29L) is provided with an inwardly exposed metal block 31 normally in spaced relation but close to an end of the magnetic core 23.

85 It is now obvious that when the alternating current energizes the magnetic core 23 the plates or blocks 31 are drawn inwardly 90

alternately thus oscillating the levers 29R—29L alternately pulling the bars 28R or 28L and oscillating lever 26 which in turn oscillates shaft 27 and 25 is oscillated in a vertical plane and its hammer 24 strikes the bell 15. Circuit is closed of course only when the tooth 13 rides the tops of the teeth 6A and is opened when it drops into the spaces between the teeth or into a deep notch 6B.

10 32 represents a wall plug through which current is available via circuit wires 33 to 21 and from core 23 by wire 34.

I claim:

15 In a bell striking device for clocks having a striking gear having a toothed rim with the usual shallow and deep notches, an oscillatable arm with a tooth normally engaging in a deep notch of said rim of the striking gear, means for rotating said gear and lifting said tooth at predetermined intervals and said tooth adapted to ride over said shallow notches until it drops into the next deep notch; sounding means comprising a hammer fixed to the lower end of an oscillatable depending arm suitably journaled to a rock shaft mounted in the upper part of the clock frame with said hammer in proximity to the clock bell, an electric circuit, a double magnetic core in said circuit and fixed in the 30 clock frame, means associated with said oscillatable arm and in said circuit for closing and opening circuit to said magnetic core to alternately magnetize its opposite ends and cause corresponding oscillation of said depending arm and bring the hammer to contact with the sounding means, and means for oscillating the depending arm comprising a beam lever fixed in vertical plane on said rock shaft, a reach rod connected to each end of said lever, each said reach rod pivotally connected at its outer end to a horizontally oscillatable lever, the free end of each said lever having a contact plate normally close to one end of said magnetic core.

45 In testimony whereof I affix my signature.
KENNETH G. WILLIAMS.
